T195.

FIG. 1 is a perspective view of a "desk lamp" showing my new design;

FIG. 2 is a front elevational view thereof;

FIG. 3 is a top plan view thereof;

FIG. 4 is a right side elevational view with respect to FIG. 2 and the opposite side is a mirror image thereof;

FIG. 5 is a back side elevational view thereof; and

FIG. 6 is a bottom plan view of the "desk lamp."

The broken lines on the support arms indicate the spiral winding to be continuous throughout.

I claim:

The ornamental design for a "desk lamp," and described as shown.
